(57) CLAIM

The ornamental design for a retrofit disc for a vehicle side washer, as shown and described.

DESCRIPTION

FIG. 1 is a top plan view of a retrofit disc for a vehicle side washer showing my new design, according to a first embodiment;

FIG. 2 is a side elevation view of FIG. 1, all the other sides being identical;

FIG. 3 is a top plan view of a retrofit disc for the vehicle side washer showing my new design, according to a second embodiment; and,

FIG. 4 is a side elevation view of FIG. 3, all the other sides being identical.

The broken lines illustrate portions of the retrofit disc for a vehicle side washer and form no part of the claimed design.
